LOUDSPEAKER

Bernard A. Engholm, Shaker Heights, Ohio, assignor to The Rola Company, Cleveland, Ohio, a corporation of Ohio

Application July 5, 1934, Serial No. 733,757

2 Claims. (Cl. 179—115.5)

This invention relates to loud speakers, such for example as those, which utilize a moving coil that operates in an air gap across a magnetic field. Speakers, which have a magnetic field that is produced by a permanent magnet usually comprise a strip which is rectangular in cross section, and which has a width that is several times the thickness. The strip is generally arranged in the form of a U and supports an inner pole piece 5 on the intermediate portion, and an outer pole piece at the ends of the arms of the U.

The inner pole piece, heretofore, so far as I am aware, has been a solid cylinder, the diameter of which has been considerably smaller than 15 the width of the magnet. I have found however, that such construction is objectionable in that it restricts the extent to which the magnet can be charged at the time of excitation. I believe that the restriction is due to the fact that the 20 pole piece, because of its small size becomes saturated before the magnet, and thereby prohibits the introduction of sufficient flux at the time of excitation to saturate the magnet. As a result, the flux distribution in the magnet does not have 25 the desired degree of uniformity, and the density is greatly impaired.

An object of my invention therefore, is to make a low reluctance pole structure, which when applied to a permanent magnet enables it to be charged to a much greater degree than any construction heretofore designed, and of which I am aware. Furthermore, my invention is directed to a construction which, when the magnet is in use will result in a field of greater intensity and of more uniform flux distribution, for 35 a magnet of a given size, and which can be made economically and readily assembled.

Referring now to the drawing, Fig. 1 is a side elevation, partly in section, of a loud speaker having a permanent field magnet; Fig. 2 is a rear view of the speaker shown in Fig. 1, but on a reduced scale, with part of the magnet broken away to show the interior construction, and Fig. 3 is a sectional view taken through the magnet 45 to show the inner pole piece in side elevation.

The loud speaker with which I have illustrated my invention has a permanent magnetic field structure, which comprises a U-shaped magnetic strip 10, to which an inner pole piece 11 is rigidly connected, adjacent the midportion thereof, and to which an outer pole piece 12 is connected at the ends thereof. Pole pieces are preferably attached to the strip 10 by welding, although other forms of connection may be utilized, if desired. The outer pole piece has an

opening 13 into which the tip of the inner pole piece extends, whereby an annular air gap is provided between the two pieces. A voice coil 14 is removably mounted on a support 15, within the air gap, and the support in turn is attached to a diaphragm 16, which is illustrated as being substantially conical in form. The interconnected support and diaphragm are shown as being attached to a centering member 17 which is rigidly fastened at its inner periphery to the neck of 10 the diaphragm and at its outer periphery to the clamping rings 19. The clamping rings in turn may be attached to a stationary diaphragm housing 20, as by securing members 21.

I have found that if the inner pole piece is 15 made solid and of uniform diameter throughout its length, and that if the diameter is less than the width of the permanent magnet, that the magnet can be charged, but that the extent of it will be materially less than if the inner pole 20 piece were made in accordance with my invention. The invention therefore, comprises a structure in which the pole tip is circular in cross-section, within the region of the air gap but is flared outwardly from such region until it is substantially equal to the width of the magnet. 25 This is particularly shown in Fig. 3. For economy of manufacture, I make the inner pole piece of laminations and fasten them rigidly together, as by rivets.

The permanent magnetic field structure, which is produced by my invention, as described, greatly increases the charge that can be imparted to the magnet at the time of excitation, and produces a structure that has more uniform flux 35 distribution over any type of pole structure heretofore used.

I claim:—

1. In a loud speaker having a permanent magnetic structure comprising a one-piece U-shaped 40 strip having substantially uniform width throughout its length, and having an inner pole piece fastened thereto, the inner pole piece comprising a plurality of flat plates which extend parallel to each other and in the same direction as the arms 45 of the U, and having an outer pole piece attached to the ends of the arms and having an opening that cooperates with the inner pole piece to provide an annular air gap, one end portion of the plates forming a cylinder and the intermediate portion of the plates being flared in 50 all planes which transversely cut the midportion of the U-shaped strip.

2. A magnetic structure for a loud speaker comprising a permanent magnetic one piece 55

strip, an outer pole piece attached to the strip and having an opening therein, an inner pole piece comprising a plurality of plates, means for holding the plates in abutting face to face relationship, each of said plates having a width equal to that of said strip adjacent its point of con-

nection thereto, the plates terminating at the opposite end in a reduced cylindrical tip which projects into the opening in the outer pole piece to provide an annular air gap.
